UNITED STATES PATENT OFFICE.

WALTER L. HARRADEN, OF LYNN, MASSACHUSETTS, ASSIGNOR TO GENERAL ELECTRIC COMPANY, A CORPORATION OF NEW YORK.

ARC-LIGHT ELECTRODE.

1,111,381.

Specification of Letters Patent. Patented Sept. 22, 1914.

Application filed March 14, 1912. Serial No. 683,748.

To all whom it may concern:

Be it known that I, WALTER L. HARRADEN, a citizen of the United States, residing at Lynn, in the county of Essex and State 5 of Massachusetts, have invented certain new and useful Improvements in Arc-Light Electrodes, of which the following is a specification.

My invention has reference to arc-light electrodes of the kind known as non-consuming positive electrodes. For the production of a luminous arc, a negative lower electrode or cathode formed of some material such as a magnetite mixture, which is 10 capable of supporting a luminous arc has been used in conjunction with an upper positive electrode or anode formed as a bar or piece of very slowly consuming material. An arc of this type is long and rather thin 15 and is easily affected by external influences, such as those exerted by air currents, and when the arc reaches the edge of the anode, it has a tendency to creep up the side of the same, thereby increasing the length of the 20 arc, which thereby frequently breaks. In a lamp of this character, the anode is frequently made of a massive metal bar of good heat conducting material, such as copper. This metal, however, is slowly but continuously oxidized both on the arcing face 25 and on the sides, particularly if the arc is run at a rather high temperature, for example, above 500 or 600 degrees C. This oxidation not only causes an unduly rapid 30 consumption of the electrode, but the oxid, which is non-conducting, accumulates on the arcing end of the anode and as this deposit increases, it becomes so heavy toward the end of the life of the anode that it is liable 35 to interfere with the proper establishment of the arc. Furthermore, when the arc runs upon this oxid, beads are formed and the arc shifting between these beads and the metal of the electrode causes an unsteadiness 40 in the light. Moreover, when such a massive bar is used for the anode, the loss in weight of the same during its life is considerable and this loss in weight seriously interferes with the regulation of the arc 45 50 when the anode is made regulating. Anodes of this general character are still spoken of as non-consuming electrodes, but this term

merely denotes that the anode consumes very much slower than the cathode.

My invention overcomes the defects hereinbefore pointed out by providing a novel form of electrode in which the arc current enters the arc in substantially equal branches which are symmetrically arranged with reference to the axis of the arc and which exert a steady influence thereon. At the same time, while my novel form of electrode is small and light as compared with anodes that have been common, its diameter is considerably larger, which in itself tends to prevent the arc from wandering to its extreme edge and creeping up the side of the same. At the same time, as the electrode is rather small, there can be no very great loss of weight during the life of the electrode to interfere with the regulation, nor will there be an undue accumulation of metallic oxid, and as the electrode is easily renewed, it may be run at a higher temperature than has hitherto been common, thereby improving the operation of the lamp.

For a fuller understanding of my invention, reference is to be had to the accompanying drawings, in which—

Figure 1 is a side elevation of one form of my electrode and of the support therefor; Fig. 2 is a plan view of Fig. 1; Fig. 3 shows a modified support for the electrode; and Fig. 4 is a side elevation of another form of my electrode and of the support therefor.

Referring to Figs. 1 and 2, the electrode is supported by wings 1—1, similar to those heretofore used, and which are ordinarily received in slots in the fume box. These wings may be connected to a regulating magnet, as is frequently done. The inner ends of the wings are bent and secured together so as to form a circular opening, but instead of an electrode in the form of a solid bar, the circular opening receives a tubular member 2 which is slidable therein. The circular portions of the wings are cut away at the top to form cam surfaces 3, which engage the heads of screws 4 suitably secured in the tube 2. The circular portions of the wings are also cut away below to form cam surfaces 5, which are reversely arranged from those at the top so that the two sur-

80

85

100

faces are substantially equi-distant throughout. The ends of the pin 6 which pass through tube 2 engage the cam surfaces 5. It is thus apparent that by rotating the tube 2, the ends of the pin 6 and the screws 4 will follow the cam surfaces 5 and 3 respectively and a bodily longitudinal movement is thereby given to the tube. Depending U shaped brackets 7 are suitably secured to the wings 1-1, and are provided near the bottom with notches 8. The electrode member 9 is cup-shaped, as shown in Fig. 3, the cylindrical portion 10 being closed at the bottom by a disk 9^a, while from the upper end of the cylinder extends outwardly a flange 11, which is received in the notches 8 of the U shaped brackets 7. In the form shown in Fig. 1, there is a pin 12 secured in the tube 2 and bent downwardly which forms a convenient means for rotating the tube when it is desired to place an electrode in position. For this purpose, the tube 2 is first raised by giving it a rotary movement, as above described, and the electrode is then placed in position with its flange in the notches 8, the opening in the top of the electrode formed by the cylindrical walls 10 registering with the tube 2. The tube is then rotated back to its original position and is received in the opening at the top of the electrode, thereby preventing lateral displacement of the same.

In the modification shown in Fig. 3, the tube 2 is provided with a single pin 6, the ends of which are received in and project through vertical slots 12 in the circular portions of the wings; by raising and lowering this pin within the slots the tube 2 may be lifted free from the electrode and again brought in contact with the bottom thereof.

In the modification shown in Fig. 4, the disk shaped portion 9^a of the electrode, which may if desired, be made comparatively massive by the conical portion 9^b to lengthen its life, is secured to an upper plate 13 by ribs 14. The plate 13 is provided with a screw threaded opening, within which is received the screw threaded end of a support 15 which, in turn, is secured to the wing 16. A locking member 17, shaped somewhat in the form of a shepherd's crook, has its staff passing through and is guided by a pair of clips 18 secured to the wing 16. The bottom of the crook 17 is bent back upon itself at 17' and the extreme end 19 is bent at right angles to the plane defined by the staff and the bent portion, and when lifted may be turned and received in an opening 20 in the radiating wing. When in the lower position, shown in full lines in Fig. 4, the lower end is located between two of the ribs 14 and prevents the electrode from being accidentally turned loose from its support and thereby dropping and breaking the globe. It will be seen that this elec-

trode is secured in position by first lifting the crook 17 into the dotted line position, the electrode is then screwed on to its support and by lowering the crook 17 the electrode is locked in position.

An electrode made in the form I have indicated, exerts a steady influence upon the arc in the following manner:—In the forms shown in Figs. 1 and 3, the current enters the disk shaped portion of the electrode upon which the arc runs, from the tubular member 2, from which it passes radially toward the central portion upon which the arc is intended to run. The current thus enters the disk shaped portion of the electrode from the outer edge and flows to the center, in what may be regarded as a large number of branches symmetrical with respect to the center and having substantially the same intensity. In the structure shown in Fig. 4, which is the preferred form, the current enters the disk shaped portion of the electrode by the ribs 14, from which the current flows to the center of the electrode in symmetrical branches, in all of which the current is substantially the same. I have discovered that when the current is thus led to the arc in branches symmetrical with respect to the arc and in all of which branches the current is substantially the same, the entering current exerts a steady influence upon the arc. It will be seen that when the arc wanders from the center of the electrode, the resistance in that side of the electrode toward which the arc has wandered is decreased, and more current will then flow to the arc from that side, and the excessive current on the one side tends to repel the arc to that side from which the smaller amount of current enters, and the result of all this is that the entering current automatically tends to keep the arc in the center of the electrode.

At the same time, contact between the electrode and the supporting wings is established, either by means of the tubular member 2 and the U shaped brackets in Figs. 1 and 3, or by means of the ribs 14, as in Fig. 4. The contact between the lower edge of the cylinder 2 with the disk member of the electrode, as shown in Figs. 1 and 3, is over a large surface but not very intimate. This contact, while sufficient to carry the requisite current, is not sufficient to act as an efficient heat conveyer; the electrode proper is therefore kept at a comparatively high temperature. In the construction shown in Fig. 4, the conduction of heat from the electrode is through the comparatively small stem or support 15, so that in this case also the electrode is maintained at a high temperature. The electrode is therefore run at a higher temperature than has heretofore been common, which results in an improved operation of the lamp, as is well

understood in the art. Furthermore the electrode being small and inexpensive may be renewed at each trim of the lamp, and in this manner a surface comparatively free from fumes and oxidation products is always presented to the arc with a consequent improvement in the operation of the lamp, and as the electrode is comparatively small and light the loss in weight of the same during the trim does not seriously interfere with the regulation of the arc by the up and down movements of this electrode.

What I claim as new, and desire to secure by Letters Patent of the United States, is:—

- 15 1. The method of steadying an arc which consists in causing the current to enter the arc at right angles thereto and in substantially equal branches symmetrical with respect to the same.
- 20 2. In combination, an electrode comprising a substantially disk shaped member the face of which forms an arcing surface, means for supporting the electrode, and for conducting the arc current to the edge of the disk shaped portion of the electrode at points removed from and substantially symmetrical with respect to the center of the disk shaped portion.
- 25 3. In combination, an electrode comprising a substantially disk shaped imperforate member provided with an arcing surface

and a portion projecting from the periphery of the disk which is adapted to support the electrode and to convey current to the same.

35

4. In combination, an electrode comprising a substantially disk shaped portion provided with an arcing surface, and a portion projecting from the periphery of the disk, means comprising said projecting portion 40 for supporting said electrode, and means cooperating with said projecting portion for locking the same in position.

5. An electrode comprising a substantially disk-shaped portion having an arcing 45 surface, and means for conveying current to the edge of the disk by a definite number of paths symmetrically disposed about the disk.

6. An electrode comprising a substantially disk-shaped portion having an arcing surface, a supporting boss, and a series of ribs joined at one end to the supporting boss and at the other end to the periphery of the disk-shaped portion and symmetrically arranged about the same.

In witness whereof, I have hereunto set my hand this 11th day of March 1912.

WALTER L. HARRADEN.
